Primary Examiner — Austin Murphy*(74) Attorney, Agent, or Firm* — Creative Technology Ltd(57) **CLAIM**

The ornamental design for a microphone sleeve, substantially as shown and described.

DESCRIPTION

FIG. 1 is a perspective view of the microphone sleeve in accordance with the present design;

FIG. 2 is a perspective exploded view of the microphone sleeve shown in FIG. 1;

FIG. 3 is a perspective view of the microphone sleeve in accordance with the present design;

FIG. 4 is a right side view of the microphone sleeve shown in FIG. 1;

FIG. 5 is a left side view of the microphone sleeve shown in FIG. 1;

FIG. 6 is a top view of the microphone sleeve shown in FIG. 1;

FIG. 7 is a bottom view of the microphone sleeve shown in FIG. 1;

FIG. 8 is an enlarged bottom right perspective view of the bottom section of the microphone sleeve shown separately for convenience of illustration;

FIG. 9 is an enlarged lower front left perspective view of the bottom section of the microphone sleeve shown separately for convenience of illustration; and,

FIG. 10 is an enlarged right side view of the bottom section of the microphone sleeve shown separately for convenience of illustration, the left side being a mirror image.

Features indicated in broken line disclosure are for exemplary purposes only, and form no part of the claimed design.
